CLAIM

The ornamental design for luminescent element with a lens, as shown and described.

DESCRIPTION

The present design is featured by a unique appearance of a luminescent element with a lens adapted to be used in a luminescent elements array for e.g. a printer.

FIG. 1 is a perspective view of a luminescent element with a lens showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a cross-sectional view taken along the A—A line in FIG. 6; and,

FIG. 9 is a top plan view showing a use condition of the luminescent element with the lens in which an array of the luminescent elements with lenses is mounted on a substrate.

The broken lines are for illustration only and form no part of the claimed design.
